UNITED STATES PATENT OFFICE.

GUY SNOW, OF KAUFMAN, TEXAS.

AERODROME.

996,153.

Specification of Letters Patent. Patented June 27, 1911.

Application filed May 12, 1910. Serial No. 560,959.

To all whom it may concern:

Be it known that I, GUY SNOW, a citizen of the United States, residing at Kaufman, in the county of Kaufman and State of 5 Texas, have invented a new and useful Aerodrome, of which the following is a specification.

This invention relates to aerodromes and its object is to provide a machine of this 10 character embodying the features of a helicopter and orthoptera whereby the machine can be readily elevated and sustained above a fixed point, means also being utilized for propelling the machine in a desired direction.

A further object is to provide a machine of this character the elevating wings of which are so constructed as to readily pass upwardly through the air but to prevent the 20 passage of air through them during their downward movement.

A further object is to provide wings arranged in series, the wings of each series being adapted to simultaneously move in opposite directions, so that a continuous force is exerted by the wings to elevate the machine.

A further object is to provide wings, which, when stationary, can be utilized as 30 sustaining planes.

A further object is to provide a novel form of elevating wheel.

A still further object is to provide an aerodrome having cars suspended therein for 35 lateral oscillation whereby lateral tilting of the machine will not result in a corresponding movement of the car.

With these and other objects in view the invention consists of certain novel details of 40 construction and combinations of parts hereinafter more fully described and pointed out in the claims.

In the accompanying drawings the preferred form of the invention has been shown.

45 In said drawings:—Figure 1 is a rear elevation of the complete machine. Fig. 2 is a side elevation of the machine, the elevating wings upon the near side thereof being removed. Fig. 3 is an enlarged end elevation 50 of one of the wings and of the arm extending therefrom. Fig. 4 is a longitudinal section through a portion of the wing, said section being on an enlarged scale. Fig. 5 is a perspective view of a portion of the wing. 55 Fig. 6 is a perspective view of one of the wing flaps. Fig. 7 is an enlarged section showing

one of the eccentrics and its frame in elevation and showing the guides engaged by the pins on the frames. Fig. 8 is a plan view of one of the elevating wheels. Fig. 9 is a horizontal section showing one form of rudder actuating mechanism which may be employed.

Referring to the figures by characters of reference 1 designates a platform of any suitable proportions and mounted at its ends upon springs 2 connected to axles 3 which are carried by supporting wheels 4. These axles may be formed with suitable braces 5 whereby displacement thereof relative to the platform 1 is prevented. Outer and inner posts 6 and 7 extend upwardly from each end of the platform at the center thereof, these posts supporting a top strip 8 extending longitudinally of the machine and which, 75 together with the posts and platform make up the main frame of the structure. A supporting rod 9 is mounted within the posts 7 and is arranged above and parallel with the platform, this rod constituting a support for 80 hangers 10 which are arranged in pairs, each pair of hangers being connected to a basket or car 11. It will be apparent therefore that the cars are capable of oscillating laterally, or, rather, of remaining stationary during 85 the lateral tilting of the main frame. Arms 12 extend laterally from the upper portions of the post 7, these arms on each post being arranged in upper and lower pairs, the arms of the upper pair constituting supports for 90 longitudinally extending guide strips 13 while the arms of the lower pair constitute supports for longitudinally extending guide strips 14. Each of the strips 13 is preferably provided with three pairs of apertures 15, 95 the apertures of the middle pair being spaced apart a distance equal to twice the distance of the apertures of either of the other pairs. Additional apertures 16 are formed within the strips 14 and are located directly under 100 and in alinement with the apertures 15. Guide pins 17 are slidably mounted within the apertures 15 and extend upwardly from frames 18 which are interposed between the strips 13 and 14. Additional guide pins 19 105 extend downwardly from these frames and are slidably mounted within the apertures 16. A shaft 20 extends longitudinally of the machine through the frames 18 and is journaled within the posts 7, this shaft being 110 parallel with the strips 13 and 14 and provided at an intermediate point with a

sprocket 21 driven by a chain 22 which receives motion from a motor 23 located on the platform 1 at a point between the cars 11.

Located within each of the frames 18 and 5 secured to the shaft 20 is an eccentric 24 the diameter of which is substantially equal to the distance between the upper and lower portions of the frame 18. The length of each frame however is considerably greater 10 than the diameter of the eccentric, so that when said eccentric rotates, the frame will only be shifted upwardly and downwardly thereby. Brackets 25 are secured upon the post 27 and extend laterally therefrom, these 15 brackets supporting pivot rods 26. Levers 27 are fulcrumed upon the rod 26 and arranged in pairs, each lever being provided at its outer end with outwardly diverging arms 28 and the said levers being arranged 20 in pairs, the levers of each pair being connected by a bar 29. The inner ends of the levers are connected to the adjoining frames 18 by means of links 30.

Secured to each of the bars 29 is a wing 25 frame made up of upper parallel longitudinally extending rods 31 connected by transversely extending parallel rods 32, these upper rods being connected, by hangers 33, with lower longitudinally extending rods 34. 30 These lower rods may be connected at their ends and at one or more intermediate points, by means of transversely extending rods 35. Brace wires 36 extend from the arms 28 and to the upper and lower rods respectively of 35 the wing frame and thus serve to hold said frame fixed relative to the arm and lever so that it will not become distorted or strained as a result of use.

The rods 32 constitute pivots for flaps 37 40 preferably formed of thin sheets of aluminum, these flaps being arranged in rows, and each row being located between two adjoining rods 31. The upper edge portion of each flap is preferably wrapped loosely 45 about the adjoining rod 32 and a laterally extending lug 38 may be extended from the lower or free end of the flap so as to normally rest on the adjoining wire 34 and thus support the flaps in an inclined position 50 under normal conditions.

Inasmuch as one bar 29 is connected to each pair of levers and there are three of these pairs at each side of the machine, it 55 will be apparent that there are three wings located at each side of the machine. The intermediate wing is of twice the width of either of the end wings and the length of all the wings is the same. The eccentrics operating the intermediate wing are disposed opposite to the eccentrics operating the end wings and it will be apparent therefore that when these eccentrics simultaneously rotate, the intermediate wing and the end wings will 60 be simultaneously moved in opposite directions.

A shaft 39 is journaled adjacent its ends within the post 7 and has a sprocket 40 thereon at an intermediate point, the said sprocket receiving motion through a chain 41 from the motor 23. Gears 42 are secured 75 to the ends of the shaft 39 and each of these gears meshes with a smaller gear 43 secured to a shaft 44 which is journaled within the platform 1 and the top strip 8. The two shafts 44 are parallel and extend a considerable distance above the strip 8, the upper portion of each shaft being provided with preferably four pairs of radially extending blades 45, the various blades being arranged at 45 degrees to each other and each blade 80 being preferably provided with brace wires 46 or the like extending from the outer end thereof to the shaft 44. The pairs of blades are arranged one above the other and, when they rotate, they have the same effect as a 85 large spiral. As shown in Fig. 8 each of the blades is preferably made up of a light skeleton frame 47 on which a covering 48 of thin aluminum, or of a light fabric, may be placed. The upper ends of the shafts 44 are 90 journaled within a connecting strip 44'.

It will be noted that the gears 42 and 43 are so located as to cause the shaft 44 to simultaneously rotate in opposite directions. The two elevating wheels made up of the blades 45 will thus act in opposition. Two propellers 49 are preferably located at the rear end of the main frame, each propeller being mounted upon a shaft 50, which is journaled on the platform 1 and is driven 100 by the motor 23 through any suitable mechanism.

A vertical rudder 51 is mounted between the front end of the platform 1 and the strip 8 and is provided with trunnions 52 journaled within the platform and top strip respectively. This rudder is preferably in the form of a right angle triangle and has laterally extending arms 53 to which are connected the ends of an actuating cord 54. This cord is preferably mounted on guide sheaves 55 mounted on arms 56 extending laterally from the adjoining post 6. It will 105 be apparent therefore that some portion of the cord 54 will always be within reach of an occupant of the adjoining car 11 no matter to what angle the frame of the machine may tilt relative to the car. It is of course to be understood that this form of rudder actuating mechanism is only one of many 110 which may be utilized for the purpose of shifting the rudder.

It will be apparent that the machine herein described can be elevated vertically or can be propelled forward during its elevation. Moreover either the wings of the elevating wheels or both may be utilized for raising the machine.

When the shaft 20 is set in motion the eccentrics 24 are simultaneously rotated and 115

cause the frames 18 to reciprocate vertically, the frames of the middle wings moving upwardly while the frames of the end wings move downwardly, and vice versa. Motion 5 is transmitted from these frames through links 30 and levers 27 to the wings. As each wing moves downwardly the flaps 37 swing upon their pivots and close the spaces between the rods 31, the said flaps 10 thus coöperating to form a plane which, in moving against the air thereunder, causes the machine to travel upwardly. During the upward movement of each wing, the flaps drop by gravity into their normal positions, and the air will not materially resist the upward movement of the wing. As the combined areas of the middle wings equal the combined areas of the end wings, and as said middle wings move oppositely to 15 the end wings, it will be apparent that during the vertical oscillation of the wings, the machine will be continuously subjected to the same lifting force and an uninterrupted upward movement will thus be imparted to 20 the machine during the actuation of the wings. After the machine has reached a predetermined height the propellers 49 may be set in motion and the operation of the wings may be stopped. The machine can 25 therefore be caused to soar, the forward movement of the wings through the air causing the flaps to close upwardly against the rods 31 so that all of the wings will thus constitute sustaining planes.

30 Instead of elevating the machine by means of the wings, the shafts 44 can be rotated so as to cause the blades 45 to elevate the machine. If preferred, also, these wheels can be operated simultaneously with the 35

wings and thus insure a more rapid ascent of 40 the machine. As has heretofore been pointed out, should the machine tilt laterally while in flight, the cars 11 will remain substantially horizontal because they are hung from the pivot rod or bar 9.

45 Various changes can of course be made in the construction and arrangement of the parts without departing from the spirit or sacrificing any of the advantages of the invention as defined in the appended claims. 50

What is claimed is:—

55 1. An aerodrome including pivotally supported members a frame connected thereto, arms upon said members and extending above and below the frame, braces connecting the arms to intermediate portions of the frame, means for oscillating the frame and members, and elements pivotally supported within the frame and movable upwardly therein to close the frame.

60 2. In an aerodrome, an elevating plane, including a frame made up of upper and lower connected members, flaps supported between the members, means for limiting the movement of the flaps in one direction 65 relative to the frame, diverging arms connected to the frame, levers extending from the arms, and brace wires diverging from said arms and connected to the frame at different points between the ends thereof.

70 In testimony that I claim the foregoing as my own, I have hereto affixed my signature in the presence of two witnesses.

GUY SNOW.
